UNITED STATES PATENT OFFICE.

CHRISTEN CHRISTENSEN, OF CHICAGO, ILLINOIS, ASSIGNOR TO THE ELECTRICAL ENGINEERS EQUIPMENT COMPANY, OF CHICAGO, ILLINOIS, A CORPORATION OF ILLINOIS.

SWITCH.

Application filed November 10, 1919. Serial No. 336,631.

To all whom it may concern:

Be it known that I, CHRISTEN CHRISTENSEN, a citizen of the United States, residing in Chicago, in the county of Cook and State 5 of Illinois, have invented a certain new and useful Improvement in Switches, of which the following is a full, clear, concise, and exact description, reference being had to the accompanying drawings, forming a part 10 of this specification.

My invention relates to switches and al-
tho particularly concerned with disconnecting
switches of the type including one or
more movable switch elements and a rotat-
able operating element thru which the switch
is opened and closed, it will be apparent,
as this description proceeds, that certain
novel features of the invention are equally
applicable in connection with switches of
20 other types.

While switches of the above general de-
scription are particularly adapted for re-
mote control, in which case the switch is
mounted upon a tower, pole or the like and
25 the rotatable operating element is actuated
from a distance as by an arrangement of
rods and levers extending to a suitable oper-
ating handle in convenient position at the
foot of the tower or other supporting struc-
ture, they are, as will be hereinafter made
30 apparent, by no means limited to such use
or purpose only.

Heretofore, in associating a single rotat-
able operating element with two or more
35 independent switch units, particularly when
high or relatively high tension current has
been involved, the failure of the insulation
between the various independent switch
units has been a source of considerable diffi-
culty. A further practical difficulty has
40 been the danger of accidental contact to
which the operator has been subjected.
Furthermore, where considerable current
must be carried, and particularly where
45 relatively high tension current is involved,
the matter of providing a quick, positive
opening switch has presented a difficult prac-
tical problem.

One feature of the present invention is
50 the provision of a novel switch operating
element which will afford positive insurance
against accidental contact to which the operator
heretofore has been subjected and which
will, when associated with two or more in-

dependent switch units, insure effective in- 55
sulation between the various units.

A further feature of my invention is the
provision of a switch of the above general
type of simple and rugged construction
wherein the opening of the switch will be 60
quick and positive.

Various other advantages of my invention
and novel structural details will appear
from the following detailed description, and
from the accompanying drawings, in which: 65

Figure 1 is a front elevational view of a
switch embodying the features of my in-
vention;

Figure 2 is a side elevational view of the
same; 70

Figure 3 is an enlarged longitudinal ele-
vation partly in section, of the rotatable
switch operating element;

Figure 4 is a front elevational view of a
modification; 75

Figure 5 is a side elevational view of the
same;

Figure 6 is a side elevational view of a
further modification;

Figure 7 is a rear elevational view of the 80
same with the rear closure plate broken
away; and

Figure 8 is a detail section taken sub-
stantially on the line 8-8 of Figure 7,
showing the interconnection between the 85
rotatable operating element and the movable
switch elements.

Referring first to Figures 1, 2 and 3 of
the drawings, the particular switch shown
includes a pair of movable switch elements 80
1 and 2. Each of these movable switch ele-
ments comprises an upper pair of trussed
blades 3 clamped at their lower ends and
a lower pair of blades 4 clamped at their
upper ends by means of the hinge bolts 6 85
and suitable spring washers to the out-
wardly extending hinged jaws of the hinge
terminals 5 of the switch as shown. The
upper trussed blades 3 are spaced within
their length by means of suitable channeled 90
spacing pieces interposed therebetween.

The hinge terminals 5 are mounted thru
angle brackets 17 upon the tops or outer
ends of the inclined insulators 7. The lower
ends of the insulators 7 are mounted upon 105
inclined pedestals 8, which inclined pedes-
tals 8 are mounted upon mounting strips 9.
The strips 9 span and are secured at their

opposite ends to a pair of longitudinal channel irons 10 and 11 respectively.

Although immaterial in so far as the present invention is concerned, the switch in this particular instance is of the double throw type. The free ends of the upper trussed blades 3 co-operate with terminals 12 mounted thru angle brackets 17 upon the tops or ends of the inclined insulators 14. The free ends of the lower blades 4 of the switch co-operate with terminals 13 mounted thru angle brackets 17 upon the tops or outer ends of the lower insulators 14'. The upper and lower insulators 14 and 14' respectively, are mounted thru pedestals 15 upon the mounting pieces or strips 9. The pairs of blades 3 and 4 are pressed firmly against the sides of the terminals 12 and 13 respectively by means of bolts 19 and the usual co-operating spring washers. Guide members 16 provided adjacent each side of each of the terminals 12 and 13 guide the switch blades over the ends of the terminals. The line wires are connected thru the usual socket members 18 to the contact terminals 12 and 13 and to the hinge terminals 5 of the switch as shown in Figure 1.

The switch is operated thru a rotatable operating member designated as an entirety by reference character 20. This rotatable operating element in this particular instance is composed of two similar sections, although it might be made continuous or in more than two sections if so desired. That is a matter to be determined by the type of switch and the particular conditions in point. Each of the rotatable switch operating sections comprises a pair of insulators 21 and 22. Studs 23 and 24 are cemented or otherwise secured in the opposed ends of the insulators 21 and 22 respectively and project therefrom as shown. The abutting ends of these projecting studs 23 and 24 are threaded into and securely connected together by means of ordinary sleeve or pipe couplings 25. Pins 26 extending transversely thru the coupling sleeves 25 and the studs 23 and thru the coupling sleeves 25 and the studs 24 respectively, prevent accidental displacement of the coupling sleeves such as might otherwise occur due to the jar and rotary movement to which the operating member is subjected.

The opposed ends of the insulators 22 are provided with studs 35 cemented or otherwise secured therein. Sleeves 36, provided with axial projecting bearing pins or studs 37 are threaded or otherwise suitably mounted upon the projecting studs 35. The axial projecting bearing pins 37 bear in the outer end of a bearing bracket 60 and are clamped in place by means of suitable bearing caps 61 as shown. The bearing bracket 60 is mounted upon and extends from a mounting strip 62 which mounting strip

spans the channel irons 10 and 11 intermediate the mounting strips 9. The sleeves 36, which sleeves are maintained against accidental displacement by means of transverse pins 38 extending thru the sleeve and the stud 35 associated therewith are provided with arms 40 projecting downwardly therefrom as shown in Figures 1 and 2.

The free ends of the arms 40 are pivotally connected as at 41 to a forked connecting piece 42. A rod 43 mounted in the lower socketed end of the connecting piece 42 extends to and is pivotally connected at its lower end with an arm 44 fixed upon a shaft 45. The opposite ends of the shaft 45 are mounted in bearing brackets 46 and 47 respectively, which bearing brackets are mounted upon and extend from the longitudinal channel iron 11. A second arm 48 is fixed upon the shaft 45 adjacent the bearing bracket 46 and is pivotally connected at its free end with the upper end of an operating rod 49. The lower end of the operating rod 49 is so connected with an operating lever 50 pivoted on a pin 51 that upon rotation of the lever 50 the rod 49 is moved either upwardly or downwardly to rotate the shaft 45. This rotation of the shaft 45 is transmitted thru the arm 44, rod 43 and arm 40 to the rotatable switch operating element 20.

The free ends of the insulators 21 of the switch operating element 20 are provided with studs 27 cemented or otherwise secured therein. Sleeves 28 provided with axial outwardly projecting bearing pins or studs 29 are threaded or otherwise suitably mounted upon the projecting ends of the studs 27. The sleeves 28 are maintained against accidental displacement by means of transverse pins 30 extending thru the sleeve and the stud 27 associated therewith. The axially projecting bearing pins or studs 29 are mounted between the outer ends of the bearing brackets 31 and bearing caps 32 which bearing caps 32 are clamped to the brackets 31 by means of suitable set bolts 33 or the like. The bearing brackets 31 are provided with base portions 34 as shown, which base portions are secured with the hinge terminals 5 to the angle brackets 17. In this manner the bearings at the opposite ends of the rotatable operating element 20 are entirely independent of the terminals of the switch so that these terminals will not be subject to the strain to which they would be subjected were these bearings formed in connection with the terminals.

The sleeves 28 are provided with arms 52 and 53 projecting substantially radially therefrom as shown. The free ends of the arms 52 are forked to provide a pair of projecting prongs 54 between which prongs the upper trussed blades 3 are arranged. Set bolts 55 threaded through the prongs 54 co-

operate with the forward and rear faces respectively of a block 56 interposed between the blades 3. Obviously angular adjustment of the blades 3 between the prongs 54 can be readily accomplished by means of the set bolts 55 in connection with which set bolts suitable lock nuts are preferably provided. Where blocks 56 are employed in connection with the blades as has been described, sufficient clearance should be allowed between the inner faces of the blades and these blocks as shown in Figure 3 so that the blades will be full floating relative the blocks. The blocks 56 may be maintained in place by means of a pin arranged transversely through the blades and block or by providing suitable depressions in the opposite faces of the blocks for the reception of the ends of the set bolts 55. Obviously the blocks 56 could be readily dispensed with without departing from the present invention by providing the inner ends of the set bolts 55 with suitable switch blade engaging shoes.

The free ends of the radial arms 53 are forked to provide a pair of projecting prongs 65 between which prongs the lower blades 4 of the switch are arranged. Set bolts 66 threaded through the prongs 65 either co-operate with suitable blocks interposed between the blades 4 or are provided with suitable switch blade engaging shoes, substantially as has been described in connection with the arms 52.

To operate the switch, assuming the blades to be in the position shown in Figure 2, the operating lever 50 is revolved forwardly about the axis of the pivot pin 51, whereupon the rod 49 is moved downwardly rotating the shaft 45 through the arm 48. This rotation of the shaft 45 is transmitted through arm 44, rod 43 and arms 40 to the rotatable switch operating element 20, rotating this element in a counterclockwise direction (Figure 2). This counter clockwise rotation of the operating element 20 is transmitted through the radial arms 52 and 53 to the pairs of switch blades 3 and 4, forcing the blades 3 quickly and positively about the hinge bolts 6 into open position, and thereafter rotating the pairs of blades 3 and 4 about the hinge bolts as desired. As hereinbefore pointed out, angular adjustment of the various switch elements may be readily accomplished through the set bolts 55 so that these switch elements will open and close simultaneously, or one slightly in advance of the other as desired.

It will now be apparent that I have provided for opening and closing two or more independent switch units through a single rotatable operating member, at the same time effectively isolating the circuits through the various switch units from each other and from the operator and these features, to-

gether with the provision of a switch capable of quick and positive operation, are highly important aspects of my invention.

In Figures 4 and 5 I have illustrated an alternative form of my invention. In this instance the upwardly and downwardly extending blades of each of the movable switch elements 1' and 2' are formed in one piece. The arm 52' extending from the sleeve 28' instead of being forked at its outer end to provide a pair of projecting prongs is provided with a single projecting prong 70 arranged adjacent the rear edges of the upwardly extending blades of the switch element 71, as shown. Although each of the movable switch elements comprises in this instance four blades, this particular number of blades is immaterial. As in the form heretofore described the set bolts 72 carried by the projecting prongs 70 of the arms 52' may either co-operate with the rear faces of suitable blocks interposed between the blades or may be provided with suitable switch blade engaging shoes as desired. The radial arms 53' are provided with similar prongs 70' carrying set bolts 72' for co-operation with the downwardly extending portions of the blades 71.

The operation of this switch is substantially as that set forth in connection with Figures 1 and 2. Assuming the blades to be in the position shown, the operating lever 75 is revolved forwardly about the axis of the pivot pin 76, whereupon the rod 77 is moved downwardly, rotating the bell crank lever 79 about its pivot 78. This rotation of the bell crank lever 79 is transmitted through a rod 80 to the shaft 81 by means of an arm 82 fixed thereupon and then from the shaft 81 through a rod 83 to the rotatable switch operating member 20'. As before, angular adjustment of the blades about the hinge bolts 6' may be readily had through the set bolts 72 and 72'.

In Figures 6, 7 and 8 I have illustrated another modification of my invention. In this case the switch unit or units, as the case may be, are arranged within a box 90 the hinge and contact terminals 91 and 92 respectively of the switch being mounted upon insulators 93, which insulators are mounted upon and project from the forward face of the box 90.

The wires or conductors 94 are led through insulators 95 into the box 90 and are connected to the contact terminals 92 of the switch. The insulators 95 are arranged in suitable inlets provided in the inclined portion 96 of the box 90, which inclined portion 96 is overhung by the front part of the box as shown. The conductors 97, which conductors are suitably connected to the hinge terminals 91 of the switch are led out through insulators 98, arranged in the outlets provided in the bottom of the box 130

90. The box 90 is formed with an open rear wall or face, which open rear wall is provided with a suitable closure plate 99, hinged at 100.
5. The switch in this particular instance is of the single throw type although this is, of course, immaterial. Each of the movable switch elements 101, 102 and 103 comprises a pair of blades clamped at their lower ends 10 by means of hinge bolts 104 to the outwardly extending hinge jaws of the hinge terminals 91. The switch is operated through a rotatable operating element, including insulators 105, 106 and 107. These 15 insulators are coupled together and the operating element is interconnected with the various switch blades through links 108, the opposite ends of which are flanged as shown for connection with the various insulators. The hinge terminals 91 of the switch are avoided by offsetting the links 108 intermediate their length as shown.
- The offset portions of the links 108 are provided with openings through which the 25 blades of the switch extend. The front and rear walls of these open portions of the links 108 are connected through web-like portions 109 extending between each pair of blades. These web-like portions 109 are provided 30 with downwardly extending arms 110 provided with hub portions sleeved upon the hinge bolts 104 and thereby providing bearings for the rotatable operating element at intervals throughout its length.
35. The inner ends of the set bolts 112, which set bolts are threaded through the front and rear walls respectively of the open portions of the links 108 co-operate either with strips 114 or with suitable blocks interposed between the blades of the switch. Angular adjustment of the blades can be 40 readily had through the set bolts 112. One end of the rotatable switch operating element extends through the end of the box 90 and is provided with a suitable operating lever 115 having a handle 116.
- To operate the switch the handle 116 is 45 grasped and the operating lever 115 is revolved, rotating the switch operating element and forcing the blades of the switch quickly and positively into open position about the hinge bolts 104. The action of the switch is quick and positive and the insulators 105, 106 and 107 form effective 50 barriers between the individual wires and in addition insure against accidental contact to which the operator has heretofore been subjected.
- I claim:
60. 1. In combination, a rotatable switch operating member, a switch having a movable switch member mounted independently of said operating member with its axis of rotation in axial alignment with the axis of 65 rotation of said operating member and operated by rotation thereof and an operating lever for said rotatable operating member, said rotatable operating member forming an insulating barrier between said movable switch member and said operating lever.
2. In combination, an insulating member adapted for rotation, a switch having a movable switch member mounted independently of said insulating member with its axis of rotation in axial alignment with the axis of rotation of said insulating member, bearing brackets for the opposite ends of said insulating member, an operating arm extending from one end of said insulating member for operating said movable switch member upon rotation of said insulating member and an operating lever connected with the opposite end of said insulating member for rotating said member from a distance.
3. In combination, a rotatable insulating member, a switch having a movable switch member mounted independently of said rotatable insulating member with its axis of rotation in axial alignment with the axis of rotation of said insulating member, a sleeve member encircling one end of said insulating member, said sleeve member having a bearing stud and an operating arm projecting from said sleeve member for operating said switch member upon rotation of the insulating member.
4. In combination, a rotatable insulating member, a switch having a movable switch member mounted independently of said rotatable insulating member with its axis of rotation in axial alignment with the axis of rotation of said insulating member, and means carried by and rotatable with said rotatable insulating member for operating the movable switch member upon rotation of said insulating member.
5. In a switch, an insulator supporting a bearing member and a pivot terminal, a switch blade pivoted to said pivot terminal, a contact terminal, a rotatable operating member for making and breaking contact between said switch blade and said contact terminal, one end of said rotatable operating member being supported by said bearing bracket and a bearing bracket for the opposite end of said rotatable operating member.
6. In combination, a switch having a movable switch member, a rotatable member for operating said movable switch member and means for adjusting said movable switch member angularly relative to said rotatable operating member.
7. In combination, a switch having a movable switch member, an insulating member adapted for rotation, a sleeve member encircling one end of said insulating member, said sleeve member having a bearing stud and an operating member for operating said

switch member upon rotation of said insulating member, a sleeve member encircling the other end of said insulating member, said second sleeve member having a bearing stud 5 and an arm through which said insulating member is rotated.

8. In a switch, a rotatable operating member carrying a radially projecting arm, a pair of prongs projecting from said radial 10 arm, a movable switch member extending between said projecting prongs and means for adjusting said movable switch member between said prongs.

9. In combination, a switch having a 15 pivoted switch member and a rotatable operating member carrying a radially projecting arm for swinging said pivoted switch member about its pivot upon rotation of said rotatable operating member.

10. In combination, a switch having a pivoted blade, a rotatable insulating member for operating said blade, bearing brackets for the opposite ends of said rotatable insulating member, an arm carried by said 25 insulating member for operating said blade upon rotation thereof, means for adjusting said pivoted blade angularly relative to said arm, and means for rotating said insulating member.

11. In a switch, a pair of insulators, bearing brackets and pivot terminals supported thereby, switch blades pivoted to said pivot terminals, contact terminals for said switch blades, a rotatable operating member supported in said bearing brackets and adapted for making and breaking contact between 35 said switch blades and said contact terminals said rotatable operating member forming an insulating barrier between said switch blades.

12. In a switch, a rotatable operating member, switch blades pivoted independently of said member, said rotatable operating member insulating said switch blades 45 from one another and means for rotating said operating member to operate said blades.

13. In a switch, a rotatable operating member, a handle for rotating said member, switch blades pivoted independently of said operating member, said operating member forming an insulating barrier between the 50 switch blades and insulating said blades from the operating handle.

14. In combination, a switch having pivoted switch blades, an insulating operating connection between said pivoted switch blades and means for adjusting said switch blades angularly relatively said insulating 55 operating member.

15. In combination, a pair of movable switch members, pivot terminals for said members, contact terminals for said members, an insulating member adapted for rotation, said insulating member comprising

a pair of insulating sections, bearing brackets for the opposite ends of each of said insulating sections, a common operating means for rotating said insulating sections and means between the opposite ends of said insulating member and said movable switch members for making and breaking contact between said movable switch members and said contact terminals upon rotation of said insulating member.

16. In combination, a pair of movable switch members, an operating member extending between said movable switch members, pivot terminals mounting said switch members independently of said operating member, contact terminals for said switch members, an operating lever for the switch operating member, said operating member forming an insulating barrier between the movable switch members and said operating lever.

17. In combination, a pair of movable switch members, a rotatable insulating member, pivot terminals supporting the switch members independently of said insulating member, contact terminals for said switch members and arms on the opposite ends of the rotatable insulating member for swinging the movable switch member into and out of contact with said contact terminals upon rotation of said insulating member.

18. In combination, a pair of movable switch members, pivot terminals for said members, contact terminals for said members, a rotatable insulating member comprising a pair of insulating sections, sleeve members encircling the adjacent ends of said sections, said sleeve members carrying bearing studs and operating arms through which the insulating member is rotated, sleeve members encircling the other ends of said sections, said second sleeve members having bearing studs and operating members for operating said switch members upon rotation of said insulating member.

19. In combination, a movable switch member, a pivot terminal for said member, a contact terminal for said member, a pivot pin passing through said switch member and said pivot terminal, a rotatable operating member mounted upon said pivot pin for rotation thereabout, whereby contact between said switch member and said contact terminal is made and broken.

20. In a switch, pivoted switch blades, pivot pins for said blades, a rotatable member for operating said blades, the blades being pivoted independently of the rotatable operating member, said member comprising rotatable operating sections including insulating barriers between the blades.

21. In combination, a box, a switch blade in said box, a pivot pin supporting said switch blade, a rotatable switch operating element extending from said box and pro-

vided with an operating handle, said rotatable operating element including an insulating barrier between said switch blade and said handle and an operating section pivoted 5 upon said pivot pin.

22. In combination, a box, pivoted switch blades in said box, a rotatable operating member including insulating barriers between the various pivoted blades and operating sections for operating said blades upon rotation of said rotatable operating member, and means for adjusting said blades angularly relative said operating sections.

23. In an electrical switch, in combination, 15 a movable switch member, a switch operating

element, a connection between said element and said member, and means for adjusting said connection to vary the relative positions of said member and element.

24. In an electrical switch, in combination, 20 a plurality of movable switch members, a switch operating element, connection between said element and each of said members, and means for adjusting each of said connections to vary the relative positions of 25 the element and the corresponding member.

In witness whereof I hereunto subscribe my name this 3rd day of November A. D. 1919.

CHRISTEN CHRISTENSEN.
